COMBINED FENDER ORNAMENT AND
SIGNAL LIGHT

Robert Moss, Jr., Detroit, Mich.

Application October 27, 1949, Serial No. 5,741

Term of patent 14 years

(Cl. D14—18)

To all whom it may concern:

Be it known that I, Robert Moss, Jr., a citizen of the United States of America, residing in Detroit, Wayne county, Michigan, have invented a new, original, and ornamental Design for a Combined Fender Ornament and Signal Light, of which the following is a specification, reference being had therein to the accompanying drawing, forming a part thereof, wherein

Figure 1 is a side elevational view of a combined fender ornament and signal light showing my new design;

Figure 2 is a perspective view of the combined fender ornament and signal light shown in Figure 1;

Figure 3 is a plan view of the combined fender ornament and signal light;

Figure 4 is a front elevational view; and

Figure 5 is a sectional view taken on the line 5—5 of Figure 2.

The dotted lines shown in Figure 1 are for illustrative purposes only.

I claim:

The ornamental design for a combined fender ornament and signal light, substantially as shown and described.
